Designer:

Nicholas S. Vedder

NICHOLAS S. VEDDER, OF TROY, NEW YORK.

Design No. 3,325, dated January 5, 1869.

DESIGN FOR THE PLATES OF A STOVE.

The Schedule referred to in these Letters Patent and making part of the same.

To all whom it may concern:

Be it known that I, NICHOLAS S. VEDDER, of the city of Troy, in the county of Rensselaer, and State of New York, have invented or produced a new and original Design for Stove-Plates, of which the following is a full and exact description, reference being had to the accompanying photographs, in which—

Figure 1 is a side-plate, and

Figures 2 and 3 are door-plates.

Like parts are marked by the same letters in the different figures, which are made to different scales.

My new design for the side-plate A consists essentially of the corner ornaments *b c*, end mouldings *d d*, and oval centre-piece, composed of a rope-like border-moulding, *e*, vine-like ornamentation *f*, cross-frame *g*, with centre-piece *h*, end-clasps *i i i i*, and sets of upright ribs *j j j, j j j*, all shaped and arranged around and upon the oblong panel *k*, so as to appear as represented in fig. 1.

The design for the door-plate L consists of the central ornamental rectangular panel *m*, composed of the

outer moulding *n*, and series of alternate plain and ornamental ribs *o p*, and plain surfaces *q*, surrounded by the plain surface *r*, and outside rope-like moulding *e*, all shaped and arranged as represented in fig. 2; and

The design for the door-plate S consists of the compound central ornament *t u*, upon the ribbed surface-panel *v*, surrounded by a border with the rope-like moulding *e* thereon, the whole shaped and disposed so as to present an appearance like that represented in fig. 3.

What I claim as my invention or production, and desire to secure by Letters Patent, is—

The design for the stove-plates A, L, and S, as herein shown and described.

In testimony whereof, I hereunto set my hand, this 8th day of December, 1868.

NICHOLAS S. VEDDER.
